UNITED STATES PATENT OFFICE.

FREDERIC ECAUBERT, OF BROOKLYN, NEW YORK.

HAIR-SPRING AND BALANCE MOUNTING.

1,311,501.

Specification of Letters Patent. Patented July 29, 1919.

Application filed January 24, 1916. Serial No. 73,949.

To all whom it may concern:

Be it known that I, FREDERIC ECAUBERT, a citizen of the United States, residing in Brooklyn, city of New York, county of 5 Kings, and State of New York, have invented certain new and useful Improvements in Hair-Springs and Balance Mountings.

My invention relates in general to time-pieces and more particularly to the mounting and adjustment of the hair spring and balance wheel by which time is measured.

In the usual mounting of the hair spring and balance wheel in watches, an adjustment arm is provided to loosely engage an 10 intermediate portion of the hair spring between its two fixed ends, to constitute a terminus of the effective length thereof whereby the time period is established. This adjustment arm is commonly mounted on 15 the upper face of the supporting bridge while the balance wheel and hair spring are below the bridge. The supporting arm must have a projection passing from above the bridge to a plane below the bridge, so as to 20 enter the plane of the hair spring which it must engage to regulate. Consequently the range of adjustment is limited to the clearance of this portion of the adjustment arm with respect to the supporting bridge. Fur- 25 thermore, one end of the hair spring is usually fixed with respect to the bridge, whereas the other is fixed with respect to the balance staff, the result being that a normal 30 position of the balance wheel is established 35 with respect to the bridge, and its oscillations are substantially equi-distant to each side of the normal. The collet and the roller which engages the escapement arm should, on the other hand, have a normal position 40 which brings the roller in line with the center of movement of the escapement arm and the balance wheel staff, so that the movement of the escapement roller is uniform to either side of the escapement arm. The nor- 45 mal position established by securing the spring to the bridge or with respect to the bridge, may not readily conform with the normal position required by the escapement roller, and in such cases the fixed point on 50 the spring must be varied at considerable difficulty. One of the important objects of my present invention is to make this fixed point freely movable with respect to the bridge, so as to bring the normal position 55 into the requisite conformity with the loca-

tion of the escapement roller whereby uniform oscillation of the balance wheel to either side with respect to the escapement roller is effected. Another important object of the invention is to provide a flatter construction for the mounting and adjustment of the balance wheel and hair spring. Further objects of the invention are to provide a more delicate adjustment of the hair spring to make the parts more readily accessible, to improve the mounting and arrangement of spirals, and to reduce the thickness of the mechanism. Other objects and advantages of the invention, such as the facility of balancing the hair spring, balance 60 wheel and collet as a unit, will appear from a detailed description of an embodiment thereof illustrated in the accompanying drawing.

In said drawing:

Figure 1 is a front elevation of the improved mounting and adjustment for the hair spring and balance wheel;

Fig. 2 is a transverse vertical section thereof;

Fig. 3 is a top plan view thereof;

Fig. 4 is a diagram illustrating a modified form of a spiral which may be employed;

Fig. 5 is a diagram showing the method 85 of securing the two ends of an ordinary spiral which may be employed in one embodiment of my invention;

Fig. 6 is a front elevation of another embodiment of hair spring mounting and ad- 90 justment;

Fig. 7 is a central vertical section thereof; and

Fig. 8 is a detail section on line VIII— 95 VIII of Fig. 6.

Referring to said drawing, 10 indicates the bridge piece having the jewel bearing 11 secured therein by means of a plate 12 which is counter-sunk or let into the front of the bridge, so as not to project out from 100 its front face. An adjustment frame 13 provided with a frusto-conical perforation is clamped against the underneath surface of bridge 10 by means of a frusto-conical arbor disk 14 secured therein and to the 105 bridge by means of counter-sunk screws 15. The balance wheel staff 16 passes through the frusto-conical disk 14 and is journaled in the stone 11. Balance wheel 17 and collet 18 are suitably mounted on staff 16. Collet 110

18 has the inner end of hair spring 19 secured therein by wedge 20 in the usual manner and its outer end passes through a pair of yielding spring jaws 21, 22 and 23, 24 which are preferably all integral and constitute extensions of the adjustment frame 13. They are closed against their elasticity by journaled cams 25, 26, which are suitably mounted in adjacent portions of the frame 10 18. The jaws or tongues 22 and 24 being interposed between hair spring 19 and cam screws 25, 26 prevent the transmission of sliding friction from the cam screws to the hair spring, and by their resilience automatically open when the cam screws are turned into the proper positions. A pin 27 having a recess 28 for convenience of actuating the same, is mounted in a portion of frame 13 intermediate the two clamps 21, 22 15 and 23, 24 as shown clearly in Figs. 1, 2 and 3. This pin 27 has a transverse slot 29 through which the hair spring 19 passes and by which it is engaged midway between the two clamps above referred to. The frame 13 20 may be formed of ferro-nickel or phosphor-bronze, for example, while the hair spring is constructed of steel, or any other combination of materials may be employed so as to cause a differential expansion between the frame 13 and hair spring 19 with change of 25 temperature. The pin 27 may be employed to deflect that portion of the hair spring which is between the two clamps and when one of said clamps is closed, this deflection 30 will result in the drawing in of a portion of the spring through the other clamp which is left open. If the jaw near the operating or effective length of the spring is closed while the other jaw is open, this deflection 35 may take in an increment of length in the hair spring which can be delivered to the effective length upon closing the other jaw and opening the first mentioned jaw and then returning the pin 27 to its former position. The operation may be reversed by 40 either reversing the sequence of opening and closing the two clamps or reversing the actuation of the pin 27. In this way a primary adjustment of the hair spring can be 45 accomplished. Once this has been accomplished, and further delicate adjustment is desired, the clamp at that side toward which it is desired to effect a slight movement of the hair spring can be opened while the 50 clamp from which this movement is to come, is left closed, and the mechanism then subjected to a change in temperature which will cause a differential expansion resulting in the motion desired. In this way an increment 55 of length will be produced, but this increment will be passed through the open clamp. To communicate this to the effective length of the spring, it is only necessary to close the previously opened clamp and open 60 the one previously closed, while still main- 65

taining the same temperature. A reverse operation can be obtained by either reversing the temperature change or reversing the opening and closing of the clamps. This motion due to the expansion is extremely slight and will provide for an adjustment of practically exact degree, being made more and more delicate by diminishing the range of temperature which is employed. 70

It will be seen especially by reference to 75 Figs. 1, 2 and 3 that the balance and its associated parts, including the hair spring can be rotated in unison about the frusto-conical disk 14 through 360° without coming into contact with any portion of the 80 bridge 10 and also without changing the relative positions of the two fixed ends of the hair spring. This construction thus makes it possible to adjust the hair spring and to bring the position of the parts into proper 85 conformity with the location of the escape-ment arm without disturbing the adjustment.

The spiral 19 shown in Figs. 1, 2 and 3 has a reversal of curvature made by an outward 90 bend of the hair spring. The same principle may be applied to the spiral by an inward reversal as shown in Fig. 4. In this figure, 40 indicates the spiral which is understood to be suitably fixed at the staff 41 95 and passes around the outside of clamps 42 and 43 and 44, 45 before entering the clamp 42, 43 and passing through the pin 46 on its way to clamp 44, 45. In either of these two forms, the loop formed by the reversal 100 of curvature is adjacent to a part of the hair spring which is fixed at two points, whereby it may be readily bent to throw more or less of the weight to one side or another and effect a balancing of the hair spring, balance 105 wheel and collet as a unit.

In Fig. 5, an ordinary spiral 50 is secured by wedge 51 to the collet 52 and its outer end passes into the jaws 53, 54 which may be understood to represent portions of the 110 apparatus illustrated in Figs. 1, 2, 3, 6, 7 and 8.

Referring to Figs. 6, 7 and 8, 60 indicates the bridge, which has a jewel bearing 61 introduced into the outer face thereof and held 115 in place by means of a cap 62. Cap 62 is held in the depression formed in the front face of bridge 60, by means of screws 63 which pass through the bridge piece 60 and secure on the under side thereof the frusto-conical arbor disk 64 upon which the adjustment frame 65 is rotatably mounted. The staff 66 of a balance wheel 67 is journaled in the jewel bearing 61 and the inner end of a hair spring 68 is suitably secured 120 in a collet 69 carried by the staff 66. The outer end of hair spring 68 may be brought over the outer face of adjustment frame or arm 65 and introduced in axial direction into a pair of clamps constituted by the fixed 130

and movable jaws 70, 71 and 72, 73, which project at either side of the arm 65 and are operated by cam screws 74, 75 which are mounted in the yielding arms 76, 77. The fixed jaws 70 and 72 constitute rigid anvils and are substantially equi-distant from the axis of oscillation, so that when the hair spring is clamped against these two fixed anvils, it is effectively held in the desired 10 substantially circular form at these points. The arms 76, 77 are somewhat firmer than the jaws 71, 73 so as to permit the actuation of the jaws 71, 73 directly toward the jaw parts 70, 72. A counter sink 78 is formed 15 in the adjustment frame 65 between the two clamps described and beneath this counter sink 78, a rib 79 is formed to unite the outer parts with the inner portion of the adjustment frame. This rib 79 projects into the 20 balance wheel 67 so as to economize in thickness of mechanism, and the bottom of the counter sink 78 acts to arrest the inward movement of the hair spring in axial direction when the latter is introduced. The 25 space constituted by the counter sink 78 affords a convenient access to a portion of the hair spring, where a suitable implement may be inserted to aid the adjustment. The bottom of the counter sink acts as a guard to 30 prevent the tool from slipping into contact with the balance wheel 67 during this operation. In other respects the use of the adjustment frame may correspond with that referred to in connection with Figs. 1, 2 35 and 3. These adjustment frames are illustrated as maintaining a curvature of the spiral spring at that portion engaged. The entire hair spring may be mounted within a single operating plane, or the same as in the 40 Breguet spiral arrangement to bring the outer end of the spiral nearer the staff or axis of oscillation even in the apparatus constructed under the principle of Figs. 6, 7 and 8, the deflection of the outer turn in 45 these figures being illustrated merely to show the economy in thickness where the outer end of the hair spring may be disposed within the body of the adjustment arm, as distinguished from being entirely 50 beneath the under-surface thereof.

I claim:—

1. A time measuring apparatus comprising in combination a hair spring and balance wheel and an adjustment member for determining the effective length of said hair spring, said adjustment member comprising a pair of independently operative clamps spaced apart and adapted to engage the hair spring at two points outside of its 55 operating portion.

2. A time measuring apparatus comprising in combination a hair spring and balance wheel and an adjustment member for determining the effective length of said hair 60 spring, said adjustment member comprising

a pair of independently operative clamps spaced apart and adapted to engage the hair spring at two points outside of its operating portion, said adjustment member being constructed of material having a different coefficient of expansion from the material of the hair spring. 70

3. A time measuring apparatus comprising in combination a hair spring and balance wheel, an adjustment member for determining the effective length of said hair spring, said adjustment member comprising a pair of clamps spaced apart and adapted to rotate simultaneously about a common axis and means for independently controlling the 75 opening and closing of said clamps.

4. A time measuring apparatus comprising in combination a bridge piece, a hair spring and balance wheel, and an adjustment member comprising an arm movably 80 secured to said bridge and having two hair spring gripping clamps one on either side, adapted to have said hair spring inserted therein in either direction. 85

5. A time measuring apparatus comprising in combination a hair spring and balance wheel, and an adjustment member for determining the effective length of said hair spring, said adjustment member comprising a pair of clamps spaced apart and adapted 90 to have the hair spring inserted therein in a direction axially of the balance wheel and provided with means between said clamps for axially arresting the hair spring in the proper operating position. 95

6. A time measuring device comprising in combination a balance wheel, a hair spring, and means for securing the outer end of the hair spring, said means having a counter sink within the space of which the hair 100 spring is accessible for adjustment, and being adapted to receive and arrest the hair spring in axial direction, and a clamp at each side of said counter sink for gripping the hair spring. 105

7. A time measuring device comprising in combination a balance wheel, a hair spring, and a pair of hair spring clamps spaced apart at a fixed distance from each other with space between them to permit transverse movement of the portion of the hair 110 spring extending between them. 115

8. A time measuring device comprising in combination a hair spring and a regulator clamp therefor having a journaled cam for 120 effecting the clamping pressure, and a resilient jaw interposed between said journaled cam and the hair spring and held against sliding upon the hair spring to avoid the application of friction to the hair spring. 125

9. A hair spring adjustment comprising in combination a balance wheel, a hair spring having one end secured thereto, means for securing the outer end of the hair spring and means for terminating the effective length 130

thereof; said securing and terminating means being in the form of positive gripping clamps and shiftable in unison.

10. A hair spring adjustment comprising in combination a balance wheel, a hair spring having one end secured thereto, means for securing the outer end of the hair spring and means for terminating the effective length thereof; said securing and terminating means being in the form of positive gripping clamps and shiftable in unison while maintaining constant adjustment.

11. A time measuring apparatus comprising in combination, a balance wheel, and a one piece hair spring having a major interior portion of suitable spiral curvature and an outer portion curved off in the form of a loop from the spiral portion and oppositely extended in substantially a circular curve having its center at the balance wheel axis, the form of which loop may be altered to vary the balance of the hair spring, and regulating means applied to the said oppositely extended portion for terminating the effective length of the hair spring.

12. A time measuring apparatus comprising in combination, a balance wheel, and a one piece hair spring having a major interior portion of suitable spiral curvature and an outer portion curved off in the form of a loop from the spiral portion and oppositely extended in substantially a circular curve having its center at the balance wheel axis, and a clamp adapted to rigidly grip and hold the hair spring at the said oppositely extended portion, for terminating the

effective length and to facilitate manually altering the form of the loop portion in order to vary the natural distribution of the weight of the hair spring about the balance wheel axis. 40

13. A time measuring device comprising in combination a hair spring, means for terminating the effective length thereof to establish the time periodicity, means for fixing a portion of said spring beyond the terminus of such effective length and means for deflecting the portion intermediate the effective length terminus and such fixed point to vary the effective length. 50

14. A time measuring device comprising in combination a hair spring, means for terminating the effective length thereof to establish the time periodicity, and means for deflecting a portion of the hair spring beyond the terminus of the effective length in a direction substantially at right angles to its normal direction of extent to vary the effective length. 55

15. A time measuring device comprising in combination a hair spring, a positive clamp for fixing a portion of said hair spring to determine the effective length thereof, means for fixing a portion of said hair spring outside of its effective length, 65 means for opening and closing said clamp, and means for deflecting a portion of said hair spring intermediate the clamp and fixed point while said clamp is open to vary the effective length.

FREDERIC ECAUBERT.
